ADJUSTABLE HONE

John J. Palotce, Youngstown, Ohio

Application June 6, 1941, Serial No. 396,916

17 Claims.

(Cl. 51—184.3)

This invention is a novel improvement in adjustable abrasive hones; and the principal object thereof is to provide a simple, novel and efficient elongated cylindrical stone hone of relatively small diameter possessing certain novel features of construction hereinafter set forth whereby the hone, when wet or dry, will be particularly adapted for insertion into, for the purpose of grinding, machining, finishing, polishing, or boring, bearings of relatively small diameter, such as crank-shaft bearings, connecting-rod bearings, wrist pin bearings, main bearings, or the like, although the hone may be used for many other purposes.

One object of the invention is to provide a hone of the above type consisting of a spindle around which are radially shiftably mounted a plurality of segmental holders each carrying a "carborundum" hone, said holders and hones when fully contracted around the spindle forming an unbroken cylindrical grinding surface; and said holders and spindles having complementary tapered surfaces, means being also provided for shifting the spindle axially of the holders to effect an expansion or contraction of the hones with respect to the spindle to vary the effective diameter of the hone.

Further objects of the invention are to provide a hone of the above type having novel means for adjusting the spindle axially of the holders; also having novel means for yieldably maintaining the tapered surfaces of the holders and spindle in close contact while permitting shifting of the spindle; also having novel means for yieldably preventing the holders from bulging outwardly when the spindle is shifted to expand the holders with respect thereto.

Still further objects of the invention are to provide an adjustable hone of the above type having a novel indicator scale which will indicate visually the diameter to which the hone is adjusted; also to provide an adjustable hone of the above type in which the spindle is provided with centering means at each end whereby the hone assembly may be accurately ground into truly cylindrical shape; also to provide a hone of the above type in which the hone assembly is provided with spiral grooves on its exterior or grinding surface.

I will explain the invention with reference to the accompanying drawings which illustrate several practical embodiments thereof to enable others to adopt and use the same; and will summarize in the claims the novel features of con-

struction, and novel combinations of parts, for which protection is desired.

In said drawings—

Figs. 1 and 1a together show a longitudinal section through one form of adjustable hone according to my invention.

Fig. 2 is a side elevation of one of the hone holders with hone, detached from assembly.

Fig. 3 is an enlarged end view of the hone holder and hone shown in Fig. 2.

Fig. 4 is an elevation of one end of the adjustable hone.

Fig. 5 is a transverse section on line 5—5, Fig. 1a.

Fig. 6 is a transverse section on line 6—6, Fig. 1.

Fig. 7 is a transverse section on line 7—7, Fig. 1.

Fig. 8 is a transverse section on line 8—8, Fig. 1.

Fig. 9 is a plan view of the hone assembly showing the arrangement of spiral grooves formed in the periphery thereof.

Fig. 10 is a longitudinal section showing a modified means for yieldably holding the hone holders on the spindle while permitting the holders to expand or contract relative to the spindle.

Fig. 11 is a transverse section on line 11—11, Fig. 10.

Fig. 12 is an end elevation of the modification shown in Fig. 13.

Fig. 13 is a side elevation showing an indicating scale for use in adjusting the hone to various overall diameters.

Figs. 14 and 15 are detail views.

As shown in Figs. 1 to 8, the hone preferably comprises a relatively long pilot spindle 1 of somewhat greater length than that of the desired hone abrasive surface, said spindle 1 having a hexagonal tapered enlargement 1a (Figs. 1 and 6) at one end, said taper flaring outwardly towards the end of the spindle. Intermediate the ends of the spindle are one or more similar hexagonal tapered enlargements 1b having the same slope or taper as enlargement 1a and in the same direction. Adjacent the opposite end of the spindle is a similar hexagonal tapered enlargement 1c having the same slope or taper as the enlargements 1a, 1b and likewise in the same direction.

Beyond the enlargement 1c is a reduced spindle extension 1d threaded as at 1e to receive a tapped collar 2 having an axially disposed conical recess 2a on its inner face for the purpose hereinafter described. Preferably the periphery of collar 2 is knurled so that the same may readily be turned by hand to advance or retract the collar on

spindle 1. Preferably the outer face of collar 2 is provided with a hexagonal or other non-circular extension 2b for engagement by a wrench whereby the collar may be rotated with respect to spindle 1. In the spindle extension 1d is an axially disposed tapped bore 1e adapted to receive the threaded shank 3b of a non-circular centering plug 3 having an axially disposed conical recess 3a in its outer end for the purpose hereinafter described. The non-circular body of plug 3 may be engaged by a wrench whereby the spindle may be held from rotation while the collar 2 is being rotated.

In the opposite end of spindle 1 is an axial bore 1f (Figs. 1 and 6) of substantial diameter and length adapted to slidably receive a tubular member 4 housing a bolt 5 having a head 5a slidably within the outer end of tube 4, the shank of bolt 5 passing through a perforated collar 5b fixedly mounted as by threaded engagement or the like within the inner end of tube 4, the threaded end of the shank of said bolt engaging a tapped bore 1g in spindle 1 coaxial with bore 1f. Within tube 4 disposed between the head 5a of the bolt and the collar 5b is a coiled spring 6 under compression and normally urging the tube 4 inwardly of the spindle bore 1f. Fixedly mounted on the outer end of tube 4 is a collar 7 preferably threaded and locked thereon in any desired manner; and in the inner face of collar 7 is a conical recess 7a similar to the conical recess 2a of collar 2, for the purpose hereinafter described. In the outer end of head 5a of bolt 5 is a diametrical slot 5c for engagement with a screw driver or other tool whereby the bolt may be threaded into bore 1g of the spindle; and disposed axially of said bolt head 5a is a conical recess 5d, for the purpose hereinafter described.

The six faces of the tapered enlargements 1a, 1b, 1c of the spindle are adapted to slidably support six metallic blade holders 8, shown more particularly in Figs. 2, 3, 6, 7 and 8, said holders being substantially channel-shaped and extending the length of spindle 1 embracing said extensions 1a and 1c; and said holders are mounted around the spindle and are of such width that the sides thereof will abut when the holders 8 are fully retracted as shown in Figs. 7 and 8. Each holder 8 is provided with outwardly extending flanges 8a which also abut when the hone holders 8 are in fully retracted position. Each of the holders 8 carries a "Carborundum" or other hone 9 which is preferably cast into the holder, said hone 9 extending outwardly beyond the flanges 8a and having an arcuate outer periphery whereby the peripheries of all the six hones 9 when their holders 8 are in retracted position will together form a cylindrical hone in which the sides of the hones 9 in adjacent holders contact squarely as indicated in Figs. 7 and 8.

On the under side of each holder 8 at one end is a tapered surface 8b conforming with the taper of the enlargement 1a of spindle 1; and intermediate the ends of each holder 8 are one or more tapered surfaces 8c conforming with the taper of the enlargement 1b of spindle 1; and at the other end of each holder is a tapered surface 8d conforming with the taper of the enlargement 1c of spindle 1. Preferably each of the tapered surfaces 8b, 8c and 8d are of greater length than their corresponding surfaces 1a, 1b and 1c. On the undersides of the holders 8 coextensive with each of the tapered surfaces 8b, 8c and 8d are axially disposed guides 8e engaging corresponding longitudinal slots 1h in each of the

tapered surfaces 1a 1b and 1c whereby each of the holders 8 may move radially inwardly or outwardly of spindle 1 but are prevented from lateral movement thereon. By way of illustration in Fig. 6 the three holders 8 disposed below the horizontal axis of bolt 5 are shown moved radially outwardly of the shaft, whereas the three holders above the horizontal axis of bolt 5 are shown in their fully retracted positions, it being understood however that all of the sections would be simultaneously retracted or projected equal amounts at the same time as hereinafter explained.

The outer ends of the guides 8e at each end of the holders project beyond the ends of the holders and their upper faces are tapered as at 8f, said projecting ends entering, the conical recesses 2a and 7a in collars 2 and 7 and their tapers 8f to conform with the taper of the walls of the conical recesses 2a and 7a, as shown in Figs. 1 and 1a, the distance between the collars 2 and 7 being variable owing to the provision of the spring 6 interposed between the bolt head 5a and the collar 5b, and thus the tapered recesses 2a and 7a of the collars 2 and 7 are permitted to engage the correspondingly tapered ends 8f of the outermost guides 8e of the holders in all retracted or projected positions of the holders 8 to thereby yieldably maintain the tapered surfaces 8b and 8d of the holders 8 in close contact with their corresponding tapered surfaces 1a and 1c of spindle 1 for any axially adjusted position of spindle 1 with respect to the holders 8.

In order to prevent outward bulging of the relatively long holders 8 during operation or during axial adjustment of the spindle, interengaging flat springs are provided on the undersides of the holders and on the spindle 1, as illustrated in Figs. 1, 1a and 7. As shown, flat springs 8g are secured to the undersides of the holder 8 intermediate the tapered portions 8b, 8c and the tapered portions 8c, 8d, said springs being adapted to underlie cooperating flat springs 1k mounted on the reduced portions of the spindle between the tapered portions 1a, 1b, and portions 1b, 1c, said arrangement permitting the holders 8 to expand and contract with respect to the spindle 1 while yieldably urging the holders into retracted positions around the spindle.

In assembling the hone, the collar 2 would be loosened on spindle 1 sufficiently to permit the six hone holders 8 to be placed into their respective positions on the spindle with the guides 8e respectively engaging the slots 1h in the tapered enlargements 1a, 1b and 1c. In so placing the holders the flat springs 8g of the respective holders would be positioned beneath the flat springs 1k of the spindle 1 to initially hold the holders in place on the spindle while the collar 2 is moved on the spindle sufficiently to engage the tapered ends 8f of the outermost guide 8e in the conical recesses 2a and 7a of the collars 2 and 7, the tightening of the collar 2 on spindle 1 being effected either manually or by using a pair of wrenches engaging the hexagonal portion 2b of collar 2 and the centering plug 3 respectively. Further tightening of the collar 2 will shift the spindle 1 axially with respect to the assembled holders 8 (towards the right in Fig. 1a) and the sliding movement of the tapered portions 1a, 1b and 1c of spindle 1 on their related tapered portions 8b, 8c and 8d of the respective holders 8 will cause the holders to move radially outwardly while the guides

6e are retained in their respective guide slots 1h in the tapered portions of the spindle 1, said holders separating slightly during the expanding movement, as indicated by the three holders disposed below the horizontal axis of bolt 5 in Fig. 6. Since collar 1 is yieldably connected with the spindle 1 the collars 2 and 1 will merely separate slightly during expansion of the hone according to the axial movement of the spindle with respect to the holder assembly, and the tapered engagement of recesses 2a and 1a with the corresponding tapered ends 8f of the outermost guides 8e of the holders will permit the holders to move radially outwardly while at the same time the springs 6 will cause the collars to yieldably maintain the tapered portions 8b, 8d of the holders in contact with their corresponding tapered portions on their tapered seats 1a and 1c, thus forming a relatively rigid assembly for any axial adjustment of the spindle. During the expansion and contraction of the holders the interengaging flat springs 8g and 1k of the holders and spindles merely yield to such movement.

When the parts are thus assembled the hone may be placed in a power grinding machine centered by the conical recesses 3a and 5d in the outer ends of the bolt head 5a and centering plug 3 respectively and the peripheries of all of the hones 9 may be ground accurately to form a true cylindrical surface concentric with the axis of the hone or spindle.

As shown in Fig. 9 the peripheries of the hones 9 of the holders may be provided with grooves 9a which, when the holders are fully retracted, form interconnecting spiral grooves, six such spiral grooves being indicated in the drawings, said grooves providing recesses which will permit accumulations of cuttings and grinding to pass off to one side, which cuttings if not removed might build up the effective diameter of the hone and throw same off-center.

As shown in Figs. 10 and 11, a modification of the means for yieldably holding the centers of the holders against bulging may be used. In this modification the undersides of the holders 8 are provided with the same flat springs 8g shown in Figs. 1 and 1a, but instead of using the cooperating flat springs 1k on the spindle, the spindle 1 is provided with enlargements 1n each having an annular groove 1m therein in which is confined an endless spirally-coiled spring 1p to position the spring 1p axially of the spindle. The enlargements 1n are cut away as at 1q in way of the flat springs 8g of the respective hone holders 8 so as to form a series of pairs of spaced members, permitting the outer ends of the springs 8g to enter between the pairs and under the coiled spring 1p. Such arrangement will permit the holders 8 to expand and retract radially of spindle 1, and will also permit the spindle 1 to be shifted axially of the holder assembly, said springs 8g and 1p yieldably urging the holders 8 inwardly towards the axis of said spindle.

As shown in Figs. 13, 14 and 15, means are provided for visually indicating to the operator the diameter to which the hone is adjusted. In this modification the periphery of the collar 2 adjacent the ends of hones 9 is provided with an annular graduated scale 2x cooperating with a pointer 9x extending from the adjacent end of one of the hones 9, said pointer 9x overlying the surface of the scale 2x and having its edge or point disposed opposite the "zero" graduation 2y of the scale when all of the holders of hones 9 are in their fully retracted positions as indi-

cated in Fig. 13. The pointer may conveniently comprise a strip of metal 9y welded to a flange 8a of its related hone holder 8 and having its indicator portion 9x extending beyond the adjacent end of the hone so as to overlie the scale 2x as shown in Figs. 14 and 15. By such an arrangement when the collar 2 is rotated relative to the spindle, the reading of the marker 9x on the scale 2x of the collar will directly indicate the overall diameter of the expanded hone without necessitating the use of calipers or other extraneous measuring instruments.

I do not limit my invention to the exact forms shown in the drawings, for obviously changes may be made therein within the scope of the claims; and instead of using six holders and hones, as shown in the drawings, a more or less number may be similarly used where desired.

I claim:

1. An adjustable hone, comprising a spindle provided with spaced polygonal enlargements having their outer faces axially aligned and tapering at the same angle to the spindle axis and in the same direction; a plurality of longitudinally-disposed hone holders around the spindle embracing the spaced enlargements and having correspondingly tapered inner faces seated upon the corresponding aligned outer faces of the spaced enlargement; said holders corresponding in number with the number of faces of an enlargement; segmental hones in the respective holders adapted when the holders are contracted to form a cylindrical abrasive surface around the spindle; extensions at the ends of each holder having their outer faces inclined towards the axis of the spindle; a collar axially movably mounted at one end of said spindle and disposed at one end of the holders and having a conical recess receiving the adjacent holder extensions; said spindle having an axial bore in its opposite end; and a second collar at the opposite end of the holders having a tubular extension slidably engaging the bore and yieldably connected with the spindle and having a conical recess receiving the adjacent holder extensions, whereby when the spindle is moved axially of the first mentioned collar the contacting tapered surfaces of the holders and spindle will adjust the holders radially of the spindle while the said collars will yieldably retain the holders on the spindle.

2. In a hone as set forth in claim 1, the side faces of said holders and hones abutting when the holders are fully contracted around the spindle.

3. In a hone as set forth in claim 1, said hone segments having groove sections in their outer faces adapted when the holders are fully contracted to align and form complete spiral grooves around the periphery of the hone.

4. In a hone as set forth in claim 1, an annular scale on the periphery of the first mentioned collar cooperating with a pointer fixedly mounted on the end of one hone segment, whereby the diameter to which the cone is adjusted will be visually indicated.

5. An adjustable hone, comprising a spindle provided with spaced polygonal enlargement having their outer faces tapering at the same angle to the spindle axis and in the same direction, the corresponding faces of the spaced enlargements being axially aligned; a plurality of longitudinally-disposed hone holders around the spindle having correspondingly tapered inner faces seated upon the corresponding aligned

outer faces of the spaced enlargement; said holders corresponding in number with the number of faces of an enlargement; segment hones in the respective holders adapted when the holders are contracted to form a cylindrical abrasive surface around the spindle; means for preventing lateral movement of the holders on the spindle; extensions at the ends of each holder having their outer faces inclined towards the axis of the spindle; a collar axially movably mounted at one end of said spindle and disposed at one end of the holders and having a conical recess receiving the adjacent holder extensions; said spindle having an axial bore in its opposite end; and a second collar at the opposite end of the holders having a tubular extension slidably engaging the bore and yieldably connected with the spindle and having a conical recess receiving the adjacent holder extensions, whereby when the spindle is moved axially of the first mentioned collar the contacting tapered surfaces of the holders and spindle will adjust the holders radially of the spindle while the said collars will yieldably retain the holders on the spindle.

6. In a hone as set forth in claim 5, said preventing means comprising guides on the tapered inner faces of the holders engaging axially disposed longitudinal slots in the tapered faces of the spindle.

7. In a hone as set forth in claim 5, interengaging springs on the holders and spindle intermediate the ends thereof for yieldingly preventing bulging of the holders while permitting radial adjustment of the holders on the spindle.

8. In a hone as set forth in claim 5, the side faces of said holders and hones abutting when the holders are fully contracted around the spindle.

9. In a hone as set forth in claim 5, said hone segments having groove sections in their outer faces adapted when the holders are fully contracted to align and form complete spiral grooves around the periphery of the hone.

10. In a hone as set forth in claim 5, an annular scale on the periphery of the first mentioned collar cooperating with a pointer fixedly mounted on the end of one hone segment, whereby the diameter to which the hone is adjusted will be visually indicated.

11. An adjustable hone, comprising a spindle provided with spaced polygonal enlargements having their outer faces tapering at the same angle to the spindle axis and in the same direction, the corresponding faces of the spaced enlargements being axially aligned; a plurality of longitudinally disposed hone holders around the spindle, having correspondingly tapered inner

faces seated upon the corresponding outer faces of the spaced enlargements; said holders corresponding in number with the number of faces of an enlargement; segmental hones in the respective holders adapted when the holders are contracted to form a cylindrical abrasive surface around the spindle; extensions at the ends of each holder having their outer faces inclined towards the axis of the spindle; means for yieldingly preventing bulging of the holders intermediate their ends while permitting radial adjustment of the holders on the spindle; a collar axially movably mounted with respect to said spindle and disposed at one end of the holders and having a conical recess receiving the adjacent holder extensions; and a second collar at the opposite end of the holders yieldably connected with the spindle and having a conical recess receiving the adjacent holder extensions whereby when the spindle is moved axially of the first mentioned collar the contacting tapered surfaces of the holders and spindle will adjust the holders radially of the spindle while the said collars will yieldably retain the holders on the spindle.

12. In a hone as set forth in claim 11, means for preventing lateral movement of the holders on the spindle.

13. In a hone as set forth in claim 11, said preventing means comprising interengaging flat springs on the holders and spindle intermediate the ends thereof.

14. In a hone as set forth in claim 11, said preventing means comprising flat springs on the holders; and circular springs around the spindle confined between a series of pairs of spaced members on the spindle disposed intermediate the ends thereof, the flat springs entering between the pairs and underlying the circular springs.

15. In a hone as set forth in claim 11, the side faces of said holders and hones abutting when the holders are fully contracted around the spindle.

16. In a hone as set forth in claim 11, said hone segments having groove sections in their outer faces adapted when the holders are fully contracted to align and form complete spiral grooves around the periphery of the hone.

17. In a hone as set forth in claim 11, an annular scale on the periphery of the first mentioned collar cooperating with a pointer fixedly mounted on the end of one hone segment, whereby the diameter to which the hone is adjusted will be visually indicated.

JOHN J. PALOTCE.
